UNITED STATES PATENT OFFICE

2,542,724

CONTAINER DEVICE

Joseph Stettner, Chicago, Ill.

Application September 13, 1946, Serial No. 696,661

3 Claims. (Cl. 206—56)

1

This invention relates to a device for containing and carrying stacked members, such as lantern slides.

A general object of the invention is to design a novel device of particularly compact construction to facilitate the handling and transportation of stacked members.

A more specific object of the invention is to design a novel bracket which is adapted to be readily assembled and disassembled with the lid of an associated case for carrying containers, each of which may be slidably inserted into the bracket to form a novel container unit therewith constructed and arranged to contain a stack of flat members such as lantern slides.

Another object of the invention is to provide a unit such as above described which is adapted to dispense the contained members at the lower extremity thereof and to receive the members at the top thereof, whereby the stacked members are urged downwardly by force of gravity as they are removed from the bottom of the container for use by the operator as for example in a lantern slide projector.

Another object of the invention is to design a novel unit such as above described wherein the bracket which receives the container is provided with a top wall overlying the container and spaced from the adjacent end thereof to define a slot through which the contained members may be pushed upwardly, one at a time, by the operator.

A more specific object of the invention is to design a novel bracket comprising side walls flanged at the ends thereof to afford a stop for the associated container, said bracket comprising a top wall extending between the side walls and spaced from said flanges to define a slot through which the stacked members in the container may be pushed, the top wall acting as a stop or bridge to prevent accidental removal of members other than the member in said slot.

The foregoing and other objects and advantages of the invention will become apparent from the following specification and the accompanying drawings, wherein:

Figure 1 is a perspective view of a closed case or receptacle, the cover of which is adapted to support the novel unit;

Fig. 2 is a perspective view of the case from the front thereof with the cover elevated to show the novel container unit therein;

Figure 3 is a perspective view of the case from the rear thereof with the novel container unit assembled with the elevated cover which is secured in its open or elevated position;

Figure 4 is a perspective view of one of the containers;

2

Figure 5 is a perspective view of one of the containers inserted in the bracket to form a container unit therewith;

Figure 6 is a perspective view of the bracket;

Figure 7 is a fragmentary top plan view of the unit shown in Figures 2, 3, and 5;

Figure 8 is a fragmentary sectional view of the unit and case taken in a vertical plane approximately bisecting the unit longitudinally thereof;

Figure 9 is a transverse sectional view taken in the plan indicated by the line 9—9 of Figure 8 with stacked members removed.

Describing the invention in detail and referring first to Figures 1 to 3, the case or receptacle generally designated 2 comprises a lid or cover 4 hinged thereto and adapted to be locked in its closed position by a conventional latch or lock 6 on the front wall 8 of the case. The front wall 8 is provided with a handle 9 and is preferably hinged to the bottom of the case 8 as at 11 to accommodate insertion and removal of the lantern slide containers and the associated bracket hereinafter described in detail. The case 2 is preferably provided with arms 10 hinged to the sides thereof and adapted to maintain the lid 4 in its open position as seen in Figure 3.

The case 2, as illustrated, is sufficiently wide to contain three containers 12 adapted for the reception of a stack of flat members 14 such as lantern slides, and the novel bracket generally designated 16 is carried within the case in assembled relationship with one of the drawers 12 defining a novel container unit therewith having the characteristics and functions hereinafter described in detail.

Referring now to Figures 4—9, one of the containers 12 and the bracket 16 defining the container unit are shown in detail. The container 12 comprises side walls 18, an end wall 20, and a bottom wall 22 with a finger recess or opening 24 at one end thereof. The side walls 18 are provided with end flanges 26 adjacent the recess 24. The container 12 is adapted for slidable reception within the bracket 16 as best shown in Figure 5. The bracket 16 comprises side walls 28, a bottom wall 30 and a top wall 32 affording a bridge or stop over the container 12 to limit upward movement of the slides 14 except for the bottom slide which seats against the flanges 26. The side walls 28 of the bracket are provided with end flanges 34 spaced from the top wall 32 to define an exit slot or opening 35 (Figures 5—7) accommodating upward movement of the bottom slide 14, which may be urged upwardly by the finger of the operator inserted in the recess 24, the bottom wall 30 of the bracket 16 being cut away or recessed

at its rear edge as at 37 (Figure 6) to define an aperture affording access to the recess 24. The flanges 34 afford abutment for the flanges 26 of the container walls 18 to limit downward movement thereof thereby maintaining the container 12 and the bracket 16 in assembled relationship in a novel container unit which may be removably secured to the lid 4 of the case 2, as hereinafter described.

The lid 4 is provided with spaced brackets 36 and 38 which receive the bottom wall 30 of the container bracket 16, said wall 30 being conveniently offset at 40 (Figures 8 and 9) to facilitate its insertion in the brackets 36 and 38. This is accomplished by urging the wall 30 forwardly into the bracket 38 which is somewhat resilient to accommodate this action. When the rear edge of the wall 30 has passed forwardly of the bracket 38, it may be inserted into the same and urged rearwardly to the position shown in Figure 8.

The container 12 is preferably provided with a plate 42 secured to the bottom wall 22 thereof in any convenient manner and formed with lateral flanges 44 (Figure 9) adapted for engagement with flanged arms 46 of a clip 48. The arms 46 are pivoted to a pin 50 carrying a torsion spring 52 engaged with the arms 46 to resiliently urge the flanged lower extremities thereof into snug engagement with the flanges 44. The pin 50 carries a resilient pad 54 for engagement with the associated slide 14. It will be understood that by pinching the upper ends of the arms 46 together, the clip 48 may be moved along the flanges 44 to urge the slides 14 into a tight pile or stack engaged with the flanges 26. This prevents the slides from rattling in the case 2 during transportation thereof.

It may be noted that when the container unit is connected to the lid 4 of the case 2 as above described, and the lid is in its raised or open position as shown in Figure 3 the slides 14 are urged downwardly by force of gravity. Thus as the operator removes the slides one at a time from the slot 35 at the lower end of the unit, the slides move downwardly. The operator may then replace the used slides at the top of the stack.

It will be understood that I do not wish to be limited by the exact embodiment of the device shown which is merely by way of illustration and not limitation, as various and other forms of the device will, of course, be apparent to those skilled in the art, without departing from the spirit of the invention or the scope of the claims.

I claim:

1. A device of the class described comprising a receptacle having a hinged lid, an arm hinged to one side wall of the receptacle and adapted to maintain said lid in an elevated position, a bracket detachably mounted upon the top side of said lid with its axis in a plane perpendicular to the hinge line of said lid and a container slidably fitted in said bracket, said bracket having parallel side walls, a bottom wall with a recess at one end thereof and an offset portion extending longitudinally from the inner edge of said recess to the remote end edge of said bottom wall connecting said side walls, an inwardly projecting flanged portion at one end of at least one side wall, a bridge parallel to the said bottom wall connecting said side walls at their top edges and spaced from said flanged portion, said container having an open top side, an open end and a finger opening in its bottom wall in communication with the said open end, said container being mounted in said bracket with its open end in

75

abutment with the said flanged portion of the bracket and with its open top facing said bridge and defining therewith a slot for the removal of stacked articles from within said container, means on the top side of said lid removably engaging the inner edge of said bottom recess and the said remote end edge of said bottom wall within said offset bottom portion with the said finger opening of the container and the recess in the bottom wall of the bracket being disposed beyond the adjacent edge of the said lid.

2. A device of the class described comprising a receptacle having a hinged lid and having means engageable with the lid for maintaining said lid in an elevated position, a bracket detachably mounted upon the top side of said lid with its axis in a plane approximately perpendicular to the hinge line of the lid, and a container slidably fitted in said bracket, said bracket having approximately parallel side walls, a bottom wall with a recess at one end thereof and an offset portion extending longitudinally from the inner edge of said recess to the remote end edge of said bottom wall connecting said side walls, an inwardly projecting flanged portion at one end of at least one side wall, a bridge generally parallel to said bottom wall and connecting said side walls at their top edges and spaced from said flanged portion, said container having an open top side, an open end and a finger opening in its bottom wall in communication with said open end, said container being mounted in said bracket with the open end of said container in abutment with the flanged portion of the bracket and with the open top of said container facing said bridge and defining therewith a slot for the removal of stacked articles from within said container, means on the top side of said lid removably engaging the inner edge of said bottom recess and the said remote end edge of said bottom wall within said offset bottom portion with the said finger opening of the container and the recess in the bottom wall of the bracket being disposed beyond the adjacent edge of the said lid.

3. A device of the class described comprising a receptacle having a hinged lid and having means engageable with the lid for maintaining said lid in an elevated position, a bracket detachably mounted upon the top side of said lid with its axis in a plane approximately perpendicular to the hinge line of the lid, and a container slidably fitted in said bracket, said bracket having approximately parallel side walls and a bottom wall with a recess at one end thereof, an inwardly projecting flanged portion at one end of at least one side wall, a bridge generally parallel to said bottom wall and connecting said side walls at their top edges and spaced from said flanged portion, said container having an open side, an open end and a finger opening in its bottom wall in communication with said open end, said container being mounted in said bracket with the open end of said container in abutment with the flanged portion of the bracket and with the open top of said container facing said bridge and defining therewith a slot for the removal of stacked articles from within said container, means on the top side of said lid removably engaging the bracket, with the said finger opening of the container and the recess in the bottom wall of the bracket being disposed beyond the adjacent edge of the lid.

JOSEPH STETTNER.
